CURRENT CONDUCTING BAR

Lawrence C. Turnock, Cleveland Heights, Ohio

Application June 16, 1934, Serial No. 730,959

13 Claims. (Cl. 204—5)

My invention relates in general to current conducting bars, and more particularly to a sectionalized cathode bar from which articles to be plated may be suspended into a plating solution.

5 An object of my invention is the provision of a sectionalized cathode bar having a plurality of individual and insulated conducting portions from which a supporting hook carrying an article, or group of articles, may be individually and separately suspended into the plating solution.

10 Another object of my invention is to provide for selectively and separately measuring the current flowing through a plurality of cathode hooks carrying an article, or a group of articles, being plated.

15 Another object of my invention is to provide for detecting faulty electrical contact between the cathode bar and the cathode hook carrying an article, or a group of articles, being plated.

20 A further object of my invention is to provide for selectively and separately connecting the insulated conducting portions of a sectionalized cathode bar with an electrical meter to measure the current flowing through each of the insulated 15 conducting portions.

25 A further object of my invention is to provide for connecting a plurality of insulated conducting portions of a sectionalized cathode bar in parallel circuit relationship with the electrical 20 source of supply.

It is also an object of my invention to provide 30 a transfer switch having a front and back contact between which a middle contact swings, the arrangement of the contacts being such that the 35 middle contact engages the contact that it is approaching before it disengages from the contact that it is moving away from.

Other objects and a fuller understanding of my 40 invention may be had by referring to the following description taken in combination with the accompanying drawing in which like parts are designated by like reference characters, and in which:

Figure 1 is a view of a plating tank with one 45 of the sides thereof removed to illustrate more clearly the invention, and shows in addition thereto a sectionalized cathode bar embodying the features of my invention;

Figure 2 is a cross-sectional view of my section- 50 alized cathode bar shown in combination with a diagrammatic illustration of the control circuits;

Figure 3 is a fragmentary view of one of the transfer switches which is adapted to selectively connect the electrical meter in relation with its

corresponding sectionalized current conducting portion of the sectionalized cathode bar;

Figure 4 is a view similar to Figure 3, but shows the push button about half way pushed in wherein the middle contact is engaging both the front 5 and back contacts of the transfer switch, and

Figure 5 is a view similar to Figure 3, but shows the push button completely depressed wherein the middle contact is engaging the back contact 10 of the transfer switch.

With particular reference to Figure 1 of the drawing, the reference character 12 designates a cathode bar embodying the features of my invention. As illustrated, and in accordance with the general practise the cathode bar 12 is disposed longitudinally of the plating tank 10 and arranged between two anode bars 11 which are also positioned longitudinally of the plating tank. 15

As illustrated best in Figure 2, the sectionalized cathode bar 12 comprises in general an internal supporting pipe 29, an insulated tube 31 which is adapted to closely fit over the supporting pipe 29, a plurality of current conducting portions 32, 33, 34, and 35 which fit over the insulating tube 31, a plurality of insulated ring spacers 36 for 20 electrically insulating the sectionalized current conducting portions, and an insulated terminal plug 43 mounted on the right hand end of the supporting pipe 29, to which the sectionalized current conducting portions are electrically connected 25 by means of conductors 37, 38, 39, and 40. The supporting pipe 29 is preferably constructed of metal so as to make the sectionalized cathode bar sufficiently strong to carry the weight of the articles being plated. At spaced intervals there are 30 provided openings 30 along the supporting pipe 29 so that the internal conductors 37, 38, 39, and 40 may be connected to the right hand end of each 35 of the sectionalized current conducting portions 32, 33, 34, and 35. As illustrated, the left hand 40 end of the supporting pipe 29 is threaded to receive an internally threaded cap 52 having an internal shoulder for securing the insulated plug 42 against the end of the supporting pipe 29. In this manner the end of the supporting pipe 29 is 45 securely sealed, which prevents any foreign matter from entering the inside of the supporting pipe 29. The right hand end of the supporting pipe 29 is similarly threaded to receive an internally 50 threaded cap 53, which is of the same construction and dimensions as the internally threaded cap 52 mounted on the left hand end of the supporting pipe 29. To provide electrical terminals 55 for the conductors that lead to the sectionalized current conducting portions, there is employed an

insulated terminal plug 43, which is securely held against the right hand end of the supporting pipe 29. This construction also provides for sealing the right hand end of the supporting pipe 29 to prevent foreign matter from entering the inside of the sectionalized cathode bar 12.

In assembling my cathode bar 12 the threaded cap 52 and the insulated plug 42 are first mounted upon the left hand end of the supporting pipe 29. 10 Then the insulated ring 64 is inserted over the supporting pipe 29 and disposed adjacent to the threaded cap 52. After this, the insulated tube 31 is slipped over the supporting pipe 29, at the same time making the openings of the insulated 15 tube 31 register with the openings 30 of the supporting pipe 29. At this time the sectionalized current conducting portion 32 is slipped over the insulated tube 31, after which the conductor 37 may be soldered or otherwise connected to the 20 sectionalized current conducting portion 32. After this, the insulated ring spacer 36 is inserted over the insulated tube 31 and jammed against the right hand end of the sectionalized current 25 conducting portion 32. The remaining sectionalized current conducting portions 33, 34, and 35 are mounted in the same manner as the mounting of the sectionalized current conducting portion 32 just previously described. After all of the 30 sectionalized current conducting portions are properly assembled there is an insulated ring 65 inserted over the supporting pipe 29 against which the threaded cap 53 is jammed. In this construction the sectionalized current conducting portions 32, 33, 34, and 35 and the insulated ring spacer 36 35 are firmly compressed together longitudinally of their length by tightly screwing the threaded caps 52 and 53 upon the supporting pipe 29. In this manner the entire assembly of the sectionalized cathode bar is rigidly constructed so as to be able 40 to stand a great deal of hard usage. As illustrated best in Figure 2, the insulated ring spacers 36 are stepped so as to provide a good seal in order to prevent any foreign matter creeping into the inside of the supporting pipe 29 through the openings 30. Also, the insulated ring spacers 36 are somewhat raised above the surface of the sectionalized current conducting portions 32, 33, 34, and 35 so as to preserve the identity of each of the 45 sectionalized current conducting portions. This 50 prevents the operator from mounting the cathode hooks 13 over the junction of the sectionalized current conduction portions.

As illustrated in Figure 2, the sectionalized current conducting portions 32, 33, 34, and 35 are 55 respectively connected to the transfer switches 20, 21, 22, and 23. These transfer switches are adapted in the positions shown in Figure 2, to connect the sectionalized current conducting portions 32, 33, 34, and 35 in parallel circuit relation with the 60 generator 27.

With reference to Figure 3, which shows an enlarged view of one of the transfer switches, it is noted that the transfer switch includes in general a back contact 60, a front contact 61 and a middle 65 contact 59 actuated by the depressing of the push button plunger 57, which is normally biased to the right by means of a coil spring 58. The front contact is constructed of a resilient strip of material and is mounted directly on the panel board 70 11. The back contact 60 is likewise constructed of a resilient strip of material and is mounted on a block 62, which is in turn connected to the panel 75 11. The middle contact 59 is connected at its lower end directly to the panel 11, and has an intermediate portion connected to the left hand

end of the push button plunger 57 by means of a screw 63, or some other suitable means. The contacts of the transfer switch are shown in their normal positions in Figures 2 and 3. In this position the back contact 61 is engaged by the middle 5 contact 59 and electrically connects the sectionalized current conducting portions 32, 33, 34, and 35 in circuit relation with the rheostat 25 and the generator 27. The circuit for connecting the sectionalized current conducting portion 32 in circuit relation with the rheostat 25 and the generator 27 may be traced through conductors 37 and 44, the transfer switch 20, a conductor 49, the rheostat 25, a conductor 26, the generator 27 and a conductor 28, the anodes 11, the hook 14, 15 the anode slab 16, through the plating bath, the article 15 being plated which is hidden behind the end of the tank, and the cathode hook 13, which is mounted on the right hand end of the plating tank 10. The circuits for connecting the 20 sectionalized current conducting portions 33, 34, and 35 with the rheostat 25 and the generator 27 may be traced in a similar manner to the circuit just traced with respect to the sectionalized current conducting portion 32 in that the circuits 25 respectively pass through the transfer switches 21, 22, and 23.

In order to read the current flow from each of the sectionalized current conducting portions 32, 33, 34, and 35 it is only necessary for the operator 30 to press the push button plunger of the transfer switches. This connects the ammeter 18 in series with the generator 27. Thus, the current which flows through the sectionalized current conducting portion 32 and the transfer switch 20, 35 now flows upon leaving the transfer switch 20 through conductors 48 and 50, the ammeter 18, a conductor 51 and the rheostat 25, and a conductor 26 to the generator 27. The current that flows through the sectionalized current conducting portions 33, 34, and 35 and their corresponding transfer switches 21, 22, and 23 likewise flows 40 through the ammeter 18 when the transfer switches are depressed. Therefore, it is possible for the operator upon pressing the push button of 45 the selected transfer switch to determine the current flowing through the article being plated which is suspended from the selected sectionalized current conducting portion. In transferring the ammeter 18 in series with the generator 27 50 it is desirable to do this without causing arcing of the contacts, which in actual practise carry a relatively large amount of current. To make this transfer without arcing the middle contact 59 and the back contact 60, and the front contact 61, are so constructed of resilient material that the middle contact 59 engages the back contact 60 before it disengages from the front contact 61. This is shown in Figure 4. When the 55 push button plunger 57 is completely depressed the middle contact 59 engages only the back contact 60. This is shown in Figure 5. Upon the releasing of the push button plunger 57 the middle contact 59 engages the front contact 61 before it disengages from the back contact 60. 60 Accordingly, there is no interruption of the current flow.

By means of my invention it is possible at any instant during the plating operation to determine quickly and effectively the current flowing 70 through, or the rate at which the plating is taking place upon, the article or articles being plated that are suspended by each individual cathode hook from the individual sectionalized current conducting portions. The applicant finds that in 75

practise the contact resistance between the cathode hook and the cathode bar is a variable quantity, thereby causing a variation in the amount of plate received by articles of the same surface area which remain in the plating tank for the same period of time. Heretofore, in cases where the operator suspected a poor electrical contact between the engaging surfaces of a cathode hook and a cathode bar the practise has been for the operator to lift the hook from the cathode plating bar and clean both the engaging surfaces of the cathode hook and the cathode bar with sandpaper, or some other equivalent method. However, this method offered no positive assurance to the operator that he had minimized the contact resistance because when the cathode hook is resuspended on the cathode bar after the cleaning operation has taken place there is no way to determine actually the contact resistance. Thus, there is a possibility that the condition causing the high contact resistance has not been removed for the reason that in some cases the operator is unable to discern the condition causing the high resistance by observation. On the other hand, by means of my invention it is possible for the operator without removing the cathode hook from the cathode bar to determine whether or not the contact resistance between the cathode hook and the individual sectionalized current conducting portions of the cathode bar is of a low value by observing the current flowing through the ammeter by depressing the proper transfer switch. Thus, if the operator observes that the current flowing through a certain cathode hook in the plating tank is less than the current flowing through other cathode hooks in the plating tank carrying articles of equal plating area, it is an indication to the operator that the low current values are caused by a high contact resistance between the respective cathode hooks and their corresponding sectionalized current conducting portions of the cathode bar. Therefore, when the operator finds that there is a high contact resistance between one or more of the cathode hooks and the individual sectionalized current conducting portions of the cathode bar, he may take the necessary steps to remove the high contact resistance and thus reduce the time required to give the proper plating upon the articles being plated.

In practise, my sectionalized cathode bar may comprise more or less than the four sections as illustrated, and the internal wires 37, 38, 39, and 40 may be brought out through suitable openings in the insulated terminal plug 43 and soldered respectively to the conductors 44, 45, 46, and 47 without the employment of terminal members.

The supporting pipe 29 may likewise be eliminated, in which event the insulated tube 31 is made strong enough to carry the weight of the articles suspended upon the sectionalized cathode bar.

The panel 17, which carries the meter 18, the rheostat 25 and the transfer switches 20, 21, 22, and 23 may be mounted upon a wall instead of being carried by the end of the plating tank 10.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. A sectionalized supporting member comprising, in combination, a plurality of hollow current conducting members, means for supporting the said current conducting members in substantially straight alignment, means for securing the current conducting members against endwise movement upon the supporting means, means for insulating the said current conducting members from each other, and a plurality of conductors each respectively connected to the said current conducting members, said conductors being arranged internally of the hollow current conducting members. 5

2. A sectionalized supporting member comprising, in combination, a hollow supporting member, a plurality of current conducting members mounted on the supporting member, means for insulating the current conducting members from each other, a header for one end of the 20 hollow supporting member, a plurality of terminal members carried by the header, and a plurality of conductors arranged internally of the hollow supporting member, each respectively interconnecting a hollow member to a terminal 25 member. 15

3. A sectionalized bus bar adapted to be employed to support a plurality of plating hooks in relation to a plating bath comprising, in combination, a hollow and longitudinal supporting 30 member adapted to be supported above the plating bath, a plurality of sectionalized current conducting members mounted in longitudinal spaced relation and in substantially straight alignment on the hollow supporting member, means for insulating the current conducting members from each other, the arrangement of the hollow supporting member, the current conducting members, and the insulating means being such that the plurality of hooks may be suspended from 40 the sectionalized bus bar in the same bath and such that part of the said plurality of hooks are insulated from the remaining part of the 35 said plurality of hooks, and a plurality of conductors each respectively connected to the current conducting members, said conductors being arranged internally of the hollow member. 45

4. A sectionalized bus bar adapted to be employed to support a plurality of plating hooks in relation to a plating bath comprising, in combination, a hollow and longitudinal supporting member adapted to be supported above the plating bath, a plurality of sectionalized current conducting members mounted in longitudinal spaced relation and in substantially straight alignment on the hollow supporting member, means for insulating the current conducting members from each other, a portion of the insulating means being raised above the external surface of the current conducting members so as to prevent a 60 hook from contacting two adjacent ends of the current conduction members, the arrangement of the hollow supporting members, the current conducting members, and the insulating means being such that the plurality of hooks may be 65 suspended from the sectionalized bus bar in the same bath and such that part of the said plurality of hooks are insulated from the remaining part of the said plurality of hooks, and a plurality of conductors each respectively connected 70 to the current conducting members, said conductors being arranged internally of the hollow member. 75

5. A sectionalized bus bar adapted to be employed to support a plurality of hooks in relation 75

to a plating bath comprising, in combination, a hollow and longitudinal supporting member adapted to be supported above the plating bath, a hollow and longitudinal insulating member 5 adapted to be supported externally of and around the said supporting member, a plurality of hollow current conducting members mounted externally of and around the said insulating members, insulating rings mounted around the insulating member and between adjacent ends of 10 the current conducting members, a plurality of conductors each respectively connected to the current conducting members, said conductors being arranged internally of the hollow supporting member.

6. The combination of a sectionalized conducting bar from which articles may be suspended while being plated and an electrical meter to 20 read the electric condition of the articles being plated, in combination, a hollow and longitudinal supporting member adapted to be supported above the plating bath, a plurality of sectionalized current conducting members mounted in longitudinal spaced relation and in substantially straight alignment on the hollow supporting member, means for insulating the current conducting members from each other, the arrangement of the hollow supporting member, the current conducting members, and the insulating 25 means being such that the plurality of hooks may be suspended from the sectionalized bus bar in the same bath and such that part of the said plurality of hooks are insulated from the remaining part of the said plurality of hooks, and 30 a plurality of conductors each respectively connected to the current conducting members, said conductors being arranged internally of the hollow member, an electric meter, and means including switches for separately connecting the 35 conductors in circuit relation with the electric meter.

7. A sectionalized bus bar adapted to be employed to support a plurality of plating hooks in relation to a plating bath comprising, in combination, a longitudinal supporting member adapted 45 to be supported above the plating bath, a plurality of sectionalized current conducting members mounted in longitudinal spaced relation and in substantially longitudinal alignment on the supporting member, the said plurality of sectionalized current conducting members being arranged with a distance between their ends and 50 electrically insulated from each other, means for securing the current conducting members against endwise movement upon the supporting member, the arrangement of the longitudinal supporting member and the current conducting members being such that a plurality of hooks may be suspended from the sectionalized bus bar in the same 55 bath and such that part of the said plurality of hooks are insulated from the remaining part of the said plurality of hooks.

8. A sectionalized bus bar adapted to be employed to support a plurality of plating hooks in 60 relation to a plating bath comprising, in combination a longitudinal supporting member adapted to be supported above the plating bath, a plurality of sectionalized current conducting members mounted in longitudinal spaced relation and in substantially longitudinal alignment on the supporting member, the said plurality of sectionalized current conducting members being arranged with a distance between their ends and 65 electrically insulated from each other, means for securing the current conducting members against 70

endwise movement upon the supporting member, a plurality of terminal members carried by the supporting member, and a plurality of conductors for respectively interconnecting the terminal members and the current conducting members, the arrangement of the longitudinal supporting member and the current conducting members being such that a plurality of hooks may be suspended from the sectionalized bus bar in the same bath and such that part of the said plurality of hooks are insulated from the remaining part of the said plurality of hooks. 5

9. A sectionalized bus bar adapted to be employed to support a plurality of plating hooks in relation to a plating bath comprising, in combination, a longitudinal supporting member adapted to be supported above the plating bath, a plurality of sectionalized current conducting members mounted in longitudinal spaced relation and in substantially longitudinal alignment on the supporting member, the said plurality of sectionalized current conducting members being arranged with a distance between their ends and electrically insulated from each other, means for securing the current conducting members against endwise movement upon the supporting member, a plurality of conductors arranged along the supporting member and each respectively connected to the current conducting members, the arrangement of the longitudinal supporting member and the current conducting members being such that a plurality of hooks may be suspended from the sectionalized bus bar in the same bath and such that part of the said plurality of hooks are insulated from the remaining part of the said plurality of hooks. 15 20 25 30 35

10. The combination of a sectionalized conducting bar from which articles may be suspended while being plated and an electrical meter to 40 read the electrical condition of the articles being plated, in combination, a longitudinal supporting member adapted to be supported above the plating bath, a plurality of sectionalized current conducting members mounted in longitudinal spaced relation and in substantially longitudinal alignment on the supporting member, the said plurality of sectionalized current conducting members being arranged with a distance between their ends and electrically insulated from each other, means for securing the current conducting members against 45 endwise movement upon the supporting member, the arrangement of the longitudinal supporting member and the current conducting members being such that a plurality of hooks may be suspended from the sectionalized bus bar in the same bath and such that part of the said plurality of hooks are insulated from the remaining part of the said plurality of hooks, an electrical meter, and means including 50 a plurality of conductors for connecting each of the current conducting members in circuit relation with the electrical meter. 55 60 65

11. The combination of a sectionalized conducting bar from which articles may be suspended while being plated and an electrical meter to 65 read the electrical condition of the articles being plated, in combination, a longitudinal supporting member adapted to be supported above the plating bath, a plurality of sectionalized current conducting members mounted in longitudinal spaced relation and in substantially longitudinal alignment on the supporting member, the said plurality of sectionalized current conducting members being arranged with a distance between their ends and electrically insulated from each other, 70 75

means for securing the current conducting members against endwise movement upon the supporting member, the arrangement of the longitudinal supporting member and the current conducting members being such that a plurality of hooks may be suspended from the sectionalized bus bar in the same bath and such that part of the said plurality of hooks are insulated from the remaining part of the said plurality of hooks, an electrical meter, and means including a plurality of conductors and switches for separately connecting each of the current conducting members in circuit relation with the electrical meter.

12. A bus bar adapted to be employed to support a plurality of plating hooks in relation to a plating bath comprising, in combination, a longitudinal supporting member adapted to be supported above the plating bath, a plurality of current conducting members mounted longitudinally of the supporting member, the said plurality of current conducting members being electrically insulated from each other, means for securing the current conducting members to the supporting member, the arrangement of the longitudinal supporting member and the current conducting members being such that a plurality of hooks may be suspended from the bus bar in the same bath

and such that part of the said plurality of hooks are insulated from the remaining part of the said plurality of hooks.

13. The combination of a bus bar from which articles may be suspended while being plated and an electrical meter to read the electrical condition of the articles being plated, in combination, a longitudinal supporting member adapted to be supported above the plating bath, a plurality of current conducting members mounted longitudinally of the supporting member, the said plurality of current conducting members being electrically insulated from each other, means for securing the current conducting members to the supporting member, the arrangement of the longitudinal supporting member and the current conducting members being such that a plurality of hooks may be suspended from the bus bar in the same bath and such that part of the said plurality of hooks are insulated from the remaining part of the said plurality of hooks, an electrical meter, and means including a plurality of conductors for connecting each of the current conducting members in circuit relation with the electrical meter.

LAWRENCE C. TURNOCK.
